CLAIM

The ornamental design for an infant cushion unit, as shown and described.

DESCRIPTION

FIG. 1 is a perspective view of an infant cushion unit, showing my new design;

FIG. 2 is an end elevation view thereof, the opposite end being a mirror image of that shown;

FIG. 3 is a top plan view thereof;

FIG. 4 is a side elevation view thereof, the opposite side being a mirror image of that shown;

FIG. 5 is a bottom plan view thereof; and,

FIG. 6 is a perspective view of the infant cushion, showing a second embodiment of my new design. The sole difference from the first embodiment is the angular positioning of the two cushion members.

The broken lines in FIGS. 1-6 represent stitching.

FIG. 2.

FIG. 3.

FIG. 4.

FIG. 5.
